[57] CLAIM

The ornamental design for a bracket for a handle-bar of a clearing saw, as shown and described.

DESCRIPTION

FIG. 1 is a right side elevation view of a bracket for a handle-bar of a clearing saw, showing my new design;

FIG. 2 is a left side elevation view thereof;

FIG. 3 is an end elevational view thereof with the opposite end being a mirror image;

FIG. 4 is a perspective view thereof; and,

FIG. 5 is a bottom plan view thereof.
